UNITED STATES PATENT OFFICE

2,279,403

FUEL SUPPLY PUMP FOR INTERNAL COMBUSTION ENGINES

August Kottmann, Stuttgart, Germany, assignor
to Robert Bosch, Gesellschaft mit beschränkter
Haftung, Stuttgart, Germany

Application October 3, 1939, Serial No. 297,758
In Germany October 22, 1938

2 Claims. (CL 103—203)

The present invention relates to a fuel supply pump for internal combustion engines and of the type having at least one inlet valve and an auxiliary hand pump arrangement. The present invention differs from known arrangements of this type, in that the cylinder of the hand pump device is screwed directly into the housing of the fuel supply pump in place of the screw cap of the inlet valve. By this means it is a simple matter to convert fuel pumps into pumps having an auxiliary hand pumping device, by replacing the usual screw cap of the inlet valve by the cylinder of the hand pump. Moreover the device has the advantage that the housing of the fuel pump remains unchanged whether it be used as a pump with or without the hand pumping device. Thus the mounting of the pump is simplified.

The accompanying drawing shows, in Fig. 1, by way of example, a partial longitudinal section through one form of construction of a fuel pump having a hand pumping device. Fig. 2 is an enlarged fragmentary sectional view showing the inlet valve and pump connection on a larger scale.

A fuel inlet connecting element 2 and a fuel outlet connecting element 3 are screwed into a housing 1 of a fuel delivery pump. The housing 1 has a bore 5 within which is disposed an inlet valve 4. An outlet valve (not shown) is also arranged within a bore of the housing, which bore is closed by means of a screw cap or plug 28. The bore 5 is closed by the threaded part 6 of a hand pump 7 which is arranged co-axially with the valve. The element 8 has a bore 8, which

5 serves to guide a valve spindle 4a, and an annular space 10 housing a valve spring 9, which annular space is in communication with the cylindrical space within the hand pump 7 by bores or passages 18. The pump 7 has a piston 11 with a piston rod 12, and a barrel 13 within the cylinder 14. A handle 15 is attached to the upper end of the piston rod 12.

10 For the purpose of rigidly holding the piston 11 of the hand pump 7 in the position of rest, as shown in the drawing, the upper end of the piston rod is provided with a threaded part 16, which, in the rest position, is brought into threaded engagement with a complementary thread 17 within the barrel 13.

I declare that what I claim is:

1. In a mechanically operated fuel supply pump including a pump casing having a threaded opening and an inlet valve arranged in said opening, a hand-operated pump having a hollow threaded end screwed into said opening whereby said pump opens into the interior of said casing, said hollow end acting as a guide for said valve.

25 2. In a mechanically operated fuel supply pump including a pump casing having a threaded opening, and an inlet valve having a stem and a valve spring arranged in said opening, a hand-operated pump having a hollow threaded end screwed into said opening whereby said pump opens into the interior of said casing, said hollow end serving as a guide for the inlet valve stem and as a casing for the inlet valve spring.

AUGUST KOTTMANN.
